UNITED STATES PATENT OFFICE.

EUGENE BORDEN AND ALPHONSE MARTELL, OF HOLLYWOOD, CALIFORNIA.

DESIGN FOR A RADIATOR-CAP ORNAMENT.

Application filed September 28, 1927. Serial No. 23,570. Term of patent 3½ years.

To all whom it may concern:

Be it known that we, EUGENE BORDEN, a citizen of the United States, and ALPHONSE MARTELL, a citizen of France, both residing in Hollywood, in the county of Los Angeles, and State of California, have invented a new, original, and ornamental Design for Radiator-Cap Ornaments, of which the following is a specification, reference being had to the accompanying drawing, forming a part thereof.

Fig. 1 is a side elevational view of a radiator cap ornament showing our new design.

Fig. 2 is a top plan view of the ornament embodying our design.

We claim:

The ornamental design for a radiator cap ornament as shown.

EUGENE BORDEN.
ALPHONSE MARTELL.
